UNITED STATES PATENT OFFICE.

F. G. SHALLING, OF SOMERSET, MASSACHUSETTS.

IMPROVEMENT IN LOCKS.

Specification forming part of Letters Patent No. 36,919, dated November 11, 1862.

To all whom it may concern:

Be it known that I, F. G. SHALLING, of Somerset, in the county of Bristol and State of Massachusetts, have invented a new and Improved Lock; and I do hereby declare that the following is a full, clear, and exact description of the same, reference being had to the accompanying drawings, making a part of this specification, in which—

Figure 1 is an internal view of my invention, the case of the lock being bisected, as indicated by the line x x , Fig. 2; Fig. 2, a horizontal section of the same, taken in the line y y , Fig. 1; Fig. 3, a detached view of the same.

Similar letters of reference indicate corresponding parts in the several figures.

The object of this invention is to obtain a lock of simple and economical construction, which cannot be picked or illegitimately opened, and which may be applied to doors, drawers, trunks, or used in any case where a lock can be applied.

To enable those skilled in the art to fully understand and construct my invention, I will proceed to describe it.

A represents the case of the lock, which may be of rectangular form, and has three sliding tumblers, B B B, fitted within it. These tumblers are each provided with a notch, a , in their lower edges near one end of them, and into these notches the upper ends of levers C fit, said levers being all placed on one and the same fulcrum-pin b , and having springs c bearing against their lower ends, which springs have a tendency to keep the tumblers in contact with a stop, d , in the case, as will be fully understood by referring to Fig. 1. Each tumbler B has an inverted T-shaped slot, e , made in it to receive a hasp or eye, D, which passes into the case through an opening, e , in its upper edge, as shown in Fig. 1, and the springs c of the lever C have a tendency to keep the right-hand edges of the slots e in the eye D, and thereby secure the latter in the case A. In order, therefore, to release the eye D and unlock the lock, the tumblers B must be thrown back in order to bring the vertical parts of the slots e in line with each other, and, in order to render this releasing movement of the tumblers as complex as possible, the slots e may have varying positions in the tumblers, so that each of the latter will require to be

moved a different distance in order to effect the result above specified.

E represents a stop, which is formed of a horizontal plate attached to the upper end of a vertical bar, F, placed against the inner surface of one end of the case A, the bar F having a spring, G, connected to it which has a tendency to keep the stop E down back of the tumblers B and prevent them from being shoved back in order to release the eye D.

H is a plate, which is fitted on a pivot, f , in the case A, and is provided with a lip, g , which projects underneath the stop E. The plate H extends down within the path of the movement of the bits h of the key I of the lock. When the key I is inserted in the lock and turned, it first strikes against the lower part of the plate H, which is thereby turned, so that the lip g will raise the stop E, and the stop is kept elevated above the tumblers, while the bits act upon the latter and shove them so as to bring the vertical parts of the slot e in line with each other and admit of the eye D being raised out from the lock-case. By this arrangement it will be seen that the stop E must first be raised in order to admit of the tumblers B being shoved or operated, and the stop requires to be held up while the tumblers are being operated, or else it will be forced down under the action of the spring G. The stop and tumblers therefore require to be acted upon simultaneously, a result which admits of the use of the proper key only in unlocking the lock.

The lock within described is a trunk or desk lock; but the same arrangement of parts may be applied to an ordinary sliding-bolt lock with a very slight modification, which will suggest itself to any locksmith or mechanician skilled in the art.

I do not claim separately any of the within-described parts; but

I do claim as new and desire to secure by Letters Patent—

The combination of the tumblers B, stop E, and plate H with the springs c G applied, respectively, to the tumblers and stop, and all arranged to operate as and for the purpose herein set forth.

F. G. SHALLING.
